FIRE ESCAPE CABLE DRUM

Walter Schauer, Annapolis, Md.

Application January 10, 1947, Serial No. 721,378

4 Claims. (Cl. 254—159)

1

This invention relates to emergency fire escape devices and particularly devices adapted for individual use such as in hotel rooms and the like, and in particular the invention refers to a flanged drum or reel with a cable on the outer surface that may be used by an individual to lower himself from a window or the like, and the drum is provided with automatic braking means and gears that retard downward movement of the cable to prevent injury to the individual that may result from descending too rapidly.

Various types of fire escape apparatus has been provided for individual use in residences, apartments, hotels, and the like, the most common being a coil of rope beside a window. However, with one end of the rope made fast the average individual will burn his hands in attempting to slide down the rope. With this thought in mind the invention contemplates a holder for the rope wherein the rope may be let down easily and the holder is provided with centrifugally controlled retarding means wherein acceleration of the rope increases the holding force.

The purpose of this invention is to provide a simple, unique individual fire escape device by which each occupant of a hotel or the like may lower himself to safety with absolute security.

Substantially all buildings are provided with elevators, safety separated stairways, or fire escapes, but in rapidly spreading fires there are generally some people who cannot reach the elevators, stairways, and fire escapes. For this reason this invention also contemplates fire escape devices distributed at various points over the floor of a building or in each room, wherein there is always fire escape means regardless of where the fire is located in the building.

The object of this invention is, therefore, to provide a fire escape device that is always available and that may readily be used by the average individual.

Another object of the invention is to provide a fire escape device which will readily lower a person to the ground with safety without an operator or attention from an outside source.

Another object of the invention is to provide a fire escape device which will lower one person from a building and may then be rewound to lower another person, or which may be used as often as desired.

Another object of the invention is to provide an individual fire escape device which once installed, requires no attention to keep it ready for use.

Another object of the invention is to provide

2

an individual fire escape device in which the operation thereof requires no tools or the like, so that it is only necessary for an individual to affix himself to a cable thereof and jump out of a window or the like.

A further object of the invention is to provide an individual fire escape device which is comparatively simple and inexpensive so that it may be installed in substantially all hotel rooms and the like.

With these and other objects in view the invention embodies a flanged drum or reel with a cable thereon, a wall bracket on which the drum is mounted, friction brake elements in the drum, gears actuating the brake elements for centrifugal action thereof, a clutch for disengaging the gears, and means rewinding the cable on the drum.

Other features and advantages of the invention will appear from the following description taken in connection with the drawings, wherein:

Figure 1 is a view showing a front elevation of the fire escape device with the lower part of the drum broken away and shown in section.

Figure 2 is a longitudinal section through the device with parts broken away and parts in section and with the wall bracket shown in elevation.

Figure 3 is a view showing the device as it would appear in use with the drum mounted on a wall or side wall of a room in a building.

Figure 4 is a detail showing the brake actuating clutch collar.

Figure 5 is a detail showing one of the centrifugally operated weights of the brake.

Figure 6 is a cross section through one of the weights taken on line 6—6 of Figure 5.

Referring now to the drawings wherein like reference characters indicate corresponding parts the fire escape device of this invention includes a drum 10, a cable 11, and a wall bracket 12.

The drum 10 is formed with flanges 13 and 14, and a centrally disposed hub 15 in a web 16. The drum is freely rotatable on a tubular shaft 17 through the hub 15 and the shaft is fixedly mounted in the plate which forms the bracket 12 in which it is held by a lock nut 18 as shown in Figure 2. The inner end of the drum is provided with an internal gear 19 that meshes with a pinion 20 on a stud shaft 21 fixedly mounted

50 in the bracket 12, and the pinion meshes with a gear 22 on a clutch sleeve 23 which is rotatably mounted on the shaft 17 and provided with ratchet teeth 24 in the opposite end. The clutch sleeve 23 is normally held in the position shown 55 in Figure 2 wherein the teeth thereof engage cor-

responding teeth 25 in a clutch collar 26 by a spring 27 in a recess 28 in the end thereof; and when it is desired to wind the cable on the drum, the drum is rotated by a handle 29 in a clockwise direction and the teeth 24 slip off of the teeth 25 permitting the drum to rotate.

As the cable is drawn downward as shown in Figure 3 the weight of a person thereon causes the drum to rotate and as the drum rotates the gears rotate the clutch collar 26 in a direction opposite to that in which the drum is rotating and the collar rotates the weights 30 and 31 through forks 32 and 33 which are slidably mounted on flat surfaces 34 and 35 of the collar, and as the speed of rotation increases the weights will be thrown outward by centrifugal force and their outer surfaces will frictionally engage a brake band 36 on the inner surface of the drum. Therefore as the speed increases the centrifugal force will increase the friction between the weights and drum, and as the weights and drum are rotating in opposite directions, the device forms a friction brake which retards the speed of the drum. The weights are normally urged outward by springs 37 and 38 the ends of which are held on pins 39 and 40. One end of the cable is held in a socket 41 in the drum by a set screw 42, and the other end of the cable is provided with loops 43 into which the feet may be placed, with the hands holding in upper loops 44 as shown.

The wall bracket may be of any suitable shape or design and may be held to the surface of the wall by screws 45 or by any suitable means. It will also be understood that other modifications may be made in the elements without departing from the spirit of the invention.

What is claimed is:

1. In a fire escape device, a drum with flanges at the ends, a cable on said drum with one end attached thereto, a wall bracket with a shaft extending therefrom, means rotatably mounting the drum on the shaft, a clutch collar rotatably mounted on the said shaft, a releasable clutch element geared to the drum positioned to coact with the clutch collar, weights positioned in the drum slidably mounted on the collar, and a handle secured to the drum for rotation thereof.

2. In a fire escape device, a drum with flanges at the ends, a cable on said drum with one end attached thereto, a wall bracket with a shaft extending therefrom, means rotatably mounting the drum on the shaft, a clutch collar rotatably

5 mounted on said shaft, a releasable clutch element also rotatably mounted on the shaft positioned to mesh with the clutch collar, weights positioned in the drum slidably mounted on the clutch collar, and gears actuating the clutch elements by the drum to rotate the weights in a direction opposite to that in which the drum rotates.

3. In a fire escape device, a cable drum, a shaft positioned in said drum for rotatably supporting the same, a clutch collar rotatably carried on said shaft, weights slidably disposed on said collar and adapted to be rotated by said collar to urge said weights into frictional contact with said drum by centrifugal force, and driving means for said collar comprising a rotatable sleeve slidably carried on said shaft, resilient means positioned on said shaft urging said sleeve into driving engagement with said collar, and power-transmitting mechanism operatively connecting said sleeve and said drum operable upon rotation of said drum to rotate said sleeve.

4. In a fire escape device, a cable drum, a shaft positioned in said drum for rotatably supporting the same, a clutch collar rotatably carried on said shaft, weights slidably disposed on said collar and adapted to be rotated by said collar to urge said weights into frictional contact with said drum by centrifugal force, a rotatable sleeve 25 slidably carried on said shaft, and means for rotating said collar in one direction only upon rotation of said drum in the opposite direction comprising ratchet teeth on one end of said collar, ratchet teeth on the adjacent end of said sleeve, resilient means on said shaft urging said sleeve toward said collar, a gear on the end of said sleeve remote from said collar, an internal gear on said drum, and means operatively connecting said gears.
